UNITED STATES PATENT OFFICE

JOHN E. GARDNER, OF CHICAGO, ILLINOIS, ASSIGNOR TO GRIGSEY-GRUNOW COMPANY,
OF CHICAGO, ILLINOIS, A CORPORATION OF ILLINOIS

RADIO APPARATUS

Application filed August 17, 1928. Serial No. 129,717.

My invention relates in general to radio apparatus, and more particularly to such radio apparatus as employ in combination a talking machine.

5 One of the objects of my invention is to provide automatic tuning means, so that the radio receiving set will automatically function to tune in any station that may be broadcasting.

10 Another object is to provide means for automatically tuning in any predetermined station. Another object is to provide means for enabling a talking machine and radio receiving combination to function, using the 15 usual commercial sources of electrical energy, whether this energy be alternating or direct current.

Further objects are to provide an improved 20 means for automatically stopping the turn-table of the phonograph when the end of the record is reached, to provide improved means for energizing the radio receiving set when the record stops; to automatically tune in any station that happens to be broadcasting, 25 and to tune in another station when the broadcasting from the first selected station ceases, and to automatically disconnect the electric energy from the tubes employed in the machine when there is no broadcast reception 30 being had, or no record being played.

There are other objects of my invention, which, together with the foregoing, will be described in the detailed specification which 35 is to follow, reference being had to the accompanying drawing forming a part hereof.

The type of talking machine which I employ in carrying out my invention, and the apparatus employed therein has been described in my co-pending application, Serial 40 Number 123,528, filed July 19th, 1926. Reference is had to this application for a more complete description of the apparatus.

Briefly, the apparatus consists of the usual 45 talking machine of the electric reproducing type, such as the machines going under the trade names, "Electrola" and "Pantatrophe".

In accordance with the apparatus and features described in the above cited co-pending 50 application, relays are provided for control-

ling the automatic stopping of the turn-table of the machine. The automatic re-setting of the radio switch over a radio switch back, as well as the automatic tube cut-off.

Referring now to the drawing, the talking 55 machine itself comprises a tone arm (5), magnetic pick-up (6), electric motor (7), turn table (8) and the record (9). Electric energy is supplied to the machine from a source of current such as (74), and is transformed 60 by the power equipment (10), to electric energy of the character necessary to bring about the proper operation of the equipment. The power equipment (10), comprises a ballast tube (11), transformer (12), rectifiers (13 and 14), and a resistor (15) that functions 65 in a manner similar to a potentiometer, to provide means for obtaining the proper voltages necessary for operation of the device. Amplifying triodes (16 and 17) of the usual 70 type are also provided for amplifying the electric currents generated by the magnetic pick-up. The loud speaker (18) of the usual cone type is associated with the output circuit of the power amplifier (17), through 75 the transformer (19), the secondary of which is variable, so as to control the amount of energy supplied to the loud speaker. A milliammeter relay (20), is also associated 80 with the output circuit of the amplifier (17), through a transformer (46). Relays (22 and 23) of the usual type employed in the 85 automatic telephone art are adapted to be controlled by the operation of the milliammeter relay (20). The automatic stopping and re-setting device, comprising the stopping magnet (29), and the re-setting magnet (34), is essentially of the same character 90 described in the above mentioned co-pending application. The contacts (42 and 44) are also the type mentioned in the co-pending application. The contacts (42) are adapted 95 to be operated when the tone arm (5) is moved into a position that corresponds to the beginning of a record, while the contacts (44) are operated when the tone arm reaches a position shortly before the end of the record.

The radio receiving set comprises an antenna (90), that is of the aperiodic type; that 100

is, it is tuned so that it will pick up any frequency of carrier wave that is being broadcasted, a detector triode (54), an amplifier triode (57) are provided in the receiving set. The grid circuit of the detector triode is adapted to be tuned by the condenser (61). This condenser (61) is adapted to be operated by a small motor (59). The motor (59) operates the rotor of the condenser (61), 10 through gearing not shown, so that a comparatively large number of the revolutions of the motor (59) are required to rotate the rotor of the condenser through 360 degrees. The rotor of the condenser (61) is also adapted to be operated by a stepping magnet (62), 15 through a pawl and ratchet (60). A cam switch (91') is provided so that the springs are closed at all times except in a predetermined normal position of the rotor plates of 20 the condenser.

The output circuit of the amplifier (57) is adapted to be connected to the grid or input circuit of the amplifier triode (16). The output circuit of the amplifier (57) is also 25 associated with the milliammeter relay (65). The relay (66) is a latching relay having a release coil (77). The armatures (75 and 76) of the relay (66) are adapted to be maintained in operated position even when the relay (66) is de-energized by the armature (87) of the relay (77). The relay (67) is a dashpot relay. The dashpot is operated so as to give this relay a relatively long time constant 30 in operating. The time constant may be ten minutes or longer before the armature (78) closes its associated circuit. The relay (68) may be of any usual and well known type. The relay (69) is another dashpot relay, having a time constant that is considerably less 35 than the time constant of the relay (67),—say five minutes for example. The relay (70) is the usual type of telephone relay. The relay (72) is a double coil relay, and is provided with a tuned armature (86), the frequency 40 of which may be adjusted. The relay (72) may be of the usual type employed in so-called harmonic converters in the automatic telephone art. The armature (86) is tuned so as to respond to a frequency of 60 cycles. 45 The relay (71) is a high impedance relay, and is adapted to respond only to direct current.

The key (48) is a three position key, the normal position of it being shown. The operative positions are shown by the dotted lines "A" and "N A".

The push button switch (28) is employed for the initial operation of the device.

Having briefly described the apparatus 50 shown in the drawing, I will now explain its detailed operation. To assist in understanding the operation it will be assumed that the operator desires to play the phonograph without any auxiliary features. Under these 55 conditions the key (48) remains in its normal

position as shown in the drawing. The operator will press the button (28). When the push button (28) is pressed there is a circuit completed, from one side source of current (74) through the springs of the switch (28), 70 relay (66), to the other side of the source of alternating current. The relay (66) is an alternating current relay, although it will also respond to direct current. In this instance it will be assumed that alternating current 75 is obtained from source (74). The relay (66) is energized to attract its armatures (75 and 76) which are latched in operated position by the functioning of the armature (87) of the relay (77). Alternating current 80 is now connected to the primary of the transformer (12) in series with the ballast tube (11). The ballast tube (11) merely acts as a reactance to limit the current flow in this circuit. Inasmuch as there is alternating current flowing in this circuit, the high impedance relay (71) is not operated at this time. The rectifiers (13 and 14) immediately start to operate to supply direct current to the amplifying device (16 and 17). As soon 85 as the rectifiers function, the lamp (45) is lighted, so as to indicate to the operator that energy is connected to the set, and he may release the push button (28), thereby opening the circuit of the relay (66). The relay (66) is de-energized though its armatures (75 and 76) are maintained in operated condition.

The operator will now place a record (9) 90 upon the turn-table (8), and will move the tone arm (5), so as to position the needle of the magnetic pick-up (6) upon the first groove of the record. By the movement of the tone arm (5) into the starting position, the contacts (42) are closed and there is a 95 circuit completed that extends from one connection of the potentiometer (15) through the springs (42), resetting magnet (34) to the mid-point of the potentiometer. The connections on the potentiometer determine 100 the voltage in any given circuit. The mid-point of the potentiometer is zero potential. In the present instance, it has been found that 48-50 volts brings about the best operation of the relays employed. However, a 105 greater or lower voltage may be used, depending upon the design of the relays employed. The re-set magnet (34) is energized 110 to move the brake (32) from engagement with the under side of the turn-table (8), against the tension of the spring (33). The 115 brake (32) is latched in this position by the action of the extension (31) passing over the catch on the armature (30) of the release magnet (29). This operation also brings 120 about the opening of the springs (36), and the closure of the springs (35). The closure of the springs (35) completes a circuit for motor (7). The motor (7) immediately initiates the rotation of the turn-table (8), car-

rying the record (9). As the record rotates, the sound indentations in the spiral groove thereof brings about the vibration of the needle of the magnetic pick-up, and cause a variation in electrical energy in the circuit that extends to the grid of the amplifier triode (16). A resistor and condenser (91) is bridged across this circuit, so as to eliminate the usual mechanical noises obtained by the engagement of the needle with the record. The current that is applied to the grid circuit of the amplifier (16) is governed by the sound indentations in the record (9). These voice, or sound currents, are amplified and applied to the grid of the power amplifier (17). The power amplifier (17) amplifies these currents and supplies the energy to the loud speaker (18). The volume of this energy is controlled by the variable secondary 20 of the transformer (19).

The loud speaker (18) functions in the usual manner to transform the variations in electrical energy into sound waves. The amplified sound currents are also applied to the armature (21) of the milliammeter relay (20), through the small rectifier, or crystal detector (47). The detector (47) operates to rectify the alternating current and apply it to the armature (21) of the milliammeter relay (20). The armature of the milliammeter relay (20) turns so as to move the contact making member (92) away from engagement with the contact member (93). So long as there are voice currents present in the output circuit of the power amplifier (17), the contact making member (92) is operated so that it does not engage the contact member (93). Shortly after the tone arm begins its inward travel, the springs (42) are opened and the re-set magnet (34) is de-energized. However, the de-energization of this magnet is without particular function at the present time, as its armature is latched by the operation of the armature (30) of the release magnet (29).

Shortly before the end of the record, the springs (44) are brought into engagement. The point at which these springs engage is determined by the shortest record that is to be played. The springs are adjusted so as to engage shortly before the termination of the shortest record. If the records are all provided with a spiral groove, it is not necessary that such adjustment be made, so long as the springs engage before the cessation of the inward rotation of the tone arm (5). This has been explained more in detail in the above mentioned co-pending application.

When the springs (44) are brought into engagement there is a circuit completed from the connection on the potentiometer (15) through the springs (44), back contact and armature (25), slow-acting relay (23) to the mid-point of the potentiometer. The slow-acting relay (23) is energized to open a

point in the circuit of the release magnet (29) at armature (27) and to open a point in the circuit of the motor (59) at armature (26). When sound indentations in the record are no longer encountered by the magnetic pick-up, there are no sound currents present in the output circuit of the power amplifier (17), consequently the armature (21) of the milliammeter relay (20) is de-energized, and the contact making member (92) is brought into engagement with the contact member (93). A circuit is thereupon completed that extends from the connection of the potentiometer (15), through the springs (44) contact member (93), contact making member (92), relay (22), to the mid-point of potentiometer.

Relay (22) is energized to prepare a point in the circuit of relay (69), at armature (24) and to open the circuit of the slow-acting relay (23) at armature (25). The slow-acting relay (23) is de-energized for a short interval of time to complete a circuit that extends from the connection on the potentiometer (15) through the springs (44), armature (27) and its back contact, release magnet (29) to the mid-point of the potentiometer. Release magnet (29) is energized over this circuit and operates to attract its armature (30), thereby releasing the latch (31) so that it restores the normal operation of the brake (32). The brake (32) engages the underside of the turn-table (8) bringing the turn-table to rest. The cam extension (37) is operated so as to open the circuit of the motor (7) and to prepare a circuit for the relay (68). The rotation of the turn-table (8) ceases, and the record is brought to a stop.

In the event that another record is played, the tone arm is moved as before, and the operation occurs as described. In the event that no further operation is performed by the operator, the electric energy is automatically disconnected from the device. This result is brought about by the operation of the armature (24) of the relay (22), whereby a circuit is completed for the dashpot relay (67). The dashpot relay (67) is energized for a considerable interval of time to complete a circuit at its armature (78) for the release coil (77).

The release coil (77) is energized to attract its armature (87) thereby permitting the armatures (75 and 76) of the relay (66) to restore to normal. By the later operation electric energy is disconnected from the machine.

The above is the operation of the device when the talking machine or phonograph is played.

It will now be assumed that it is desired to operate the radio receiving set immediately after the desired record is played. In order to do this, the key (48) is operated to position A. The operation in playing the record proceeds substantially in the same

- manner as before described up to the energization of the relay (22), the de-energization of the relay (23) and the energization of the release magnet (29). Now when the springs (36) are closed, a circuit is complete that extends from the connection on the potentiometer springs (36), springs (52), of the key (48), relay (68) to the mid-point of the potentiometer. The relay (68) is energized to complete a circuit for the dashpot relay (69) at armature (80) and for the filament circuits of the triodes (54 and 57) at armatures (81 and 82), while at armature (83) an electrical potential is connected to the contact making member (94) of the milliammeter relay (65). By this connection there is a circuit completed for the relay (70). Relay (70) is energized, but its operation is without particular function at this time. The triodes (54 and 57) are energized to render them receptive when the condenser (61) is properly tuned, so that the input circuit of the detector (54) is resonant to a broadcast carrier frequency. If the operator does not play a record, the slow operating relay (69) is energized to operate its armature (79), thereby completing a circuit that extends from the connection on the potentiometer by way of back contact from armature (26), armature (79), motor (59) to the mid-point of the potentiometer. The motor (59) is immediately operated to bring about the rotation of the rotor of the condenser (61) at a relatively slow speed. The movement of the rotor of the condenser changes the tuning of the input circuit of the detector (54). Whenever the input circuit of the detector becomes resonant to the frequency of a carrier wave, the detector operates in the usual manner to apply the sound potentials to the input circuit of the amplifier (57) where they are amplified and applied to the amplifier (16) and thence to the power amplifier (17). The loud speaker (18) thus functions to transform the received broadcast into sound waves. As soon as any station is tuned in in this manner, the armature (21) of the milliammeter relay (20) is operated so as to bring the contact-making member (92) out of engagement with the contact member (93). The relay (22) is immediately de-energized to complete a circuit for the slow-acting relay (23) at armature (25), and to open the circuit of the relay (69) at armature (24). The relay (69) is so constructed that while it is slow to energize, its de-energization occurs relatively quickly. By the de-energization of relay (69) the circuit of the motor (59) is opened, and the rotation of the rotor of the condenser ceases. The energization of the slow-acting relay (23), also opens another point in the circuit of the motor (59) at armature (26), and opens the circuit of the release magnet (29) at armature (27). The

cessation of the motor operation as described causes the cessation of the movement of the rotor of the condenser (61), and consequently the input circuit of the detector (54) remains resonant to the frequency of the station that has been tuned in. It will thus be seen that by the functioning of the device described, a broadcasting station may be automatically selected by the radio receiving set. 75

For proper tuning operations, the contacts (92 and 93) of the milliammeter (20) may be adjusted so that it requires a considerable amount of current flowing through the armature (21) to cause the contact to disengage. This will insure that the station tuned in, will have the desired volume. Of course this volume may also be adjusted by the operation of the transformer (19). 80

During the momentary pauses in the broadcast, the contacts (92 and 93) may be closed, and the slow-acting relay (23) will be de-energized to complete a circuit for the slow operating relay (69). The time constant of the relay (69) is so fixed that the armature (79) will not engage its contacts for a longer interval of time than that that occurs in the broadcast, consequently the energization of this relay is without particular function. Inasmuch as the relays (22 and 23) are intermittently operated there may be some sparking at the contacts, which may cause noises in the radio receiving set. However, this sparking may be entirely eliminated by the use of non-inductive resistance and condensers that are usually employed in the telephone art. 95

If still further precaution is desirable, relay equipment may be enclosed in an iron case, and this case grounded so that the radio set will be effectively shielded. Whenever the relay (22) is energized upon the contacts (92 and 93) closing, a circuit is completed for the slow to operate relay (67), but this relay has a longer time constant than the relay (69), consequently its operation will be without particular function during the broadcasting. 105

When the broadcasting station signs off, there will be no sound component present in the current in the output circuit of the power amplifier (17). The armature (21) of the relay (20) will be de-energized and the contacts (92 and 93) will be closed to complete a circuit for the relay (22). The relay (22) is energized for a short interval of time to complete a point in the circuit of the motor (59). By the operation of the armature (24) of the relay (22) a circuit is completed for the slow to operate relay (69). After a considerable period of time the slow to operate relay (69) causes its armature to engage its contacts thereby completing the circuit for the motor (59). The motor (59) functions in the same manner as before to tune in an- 115

other broadcasting station, if it happens to be operating at this time. The tuning in of this station and the stopping of the motor occurs in substantially the same manner as before. Broadcasting stations will continue to be tuned in consecutively, so long as there are any stations broadcasting.

If there are no stations broadcasting, the voice current relay (20) will not be operative, and the slow to operate relay (67) will have sufficient time interval to cause its armatures to engage their associated contacts, thereby completing the circuit for the relay (77). The relay (77) functions to disconnect the energy from the equipment in the manner before described. All the relays in the device are thereupon de-energized, and their associated circuits are restored to normal.

20 In the event that it is desired to shut down the radio receiving set at any time, the key (48) is restored to its neutral position, whereupon the circuit of the relay (68) is open, so that the automatic tuning equipment, and 25 the radio receiving equipment is disconnected. The relay (67) then functions as before to bring about the disconnection of the electrical energy from the device.

It sometimes occurs that while one is 30 listening to a broadcast reception the station requests that the listeners stand by for an interval of time. In order to relieve the monotony of this wait, it is sometimes desirable that the phonograph be placed in operation. It may be that at this time a play is 35 being broadcast, or something of that nature, and it is not desired to miss any of the broadcast. In order to bring about proper functioning of the equipment in these conditions, the key (48) is brought to the position N A, and the phonograph is started in the same manner as before described. When the key 40 is thrown into position N A the spring (51) is caused to engage its working contact, whereby a circuit is completed from the connection on the potentiometer (15) working 45 contact of spring (51), and said relay (68) to the mid-point of the potentiometer. The relay (68) is energized over this circuit to 50 energize the radio receiving set, and to complete a circuit for the relay (70) at armature (83) over a path that extends from the connection on the potentiometer (15), armature (83) in its front contacts, contacts (94) relay 55 (70) to the mid-point of the potentiometer.

The relay (70) is energized to open a point in the circuit of the release magnet (29). The operation of the springs (50) of the key (48) serves to prepare a point on the circuit of the 60 release magnet (29). When the tone arm (5) is moved to its original position, re-set magnet (34) functions as before.

So long as the broadcasting station does 65 not again start to broadcast, the record will continue to play. When the record is

through playing, the rotation of the turn-table will be stopped by the operation of the relay (23) in the same manner as before described. Another record may be played in the same manner. It will be assumed that 70 while one of these records is being played, the broadcasting is resumed. Under these conditions the voice current relay (65) is operative to cause the opening of the springs (94). The relay (70) is thereupon de-energized 75 to complete a circuit for the release magnet (29). The release magnet (29) functions to bring the turn-table to rest, and to disconnect the motor (7). Inasmuch as the radio receiving set is connected 80 with the loud speaker, the broadcast reception is continued as before.

It will be noted that the magnetic pick-up is connected to the grid of the amplifier (16) as well as to the secondary of the transformer 85 (58). The current in this circuit is relatively small, and will not affect the operation of the relay (65) to prevent it from functioning in the manner described. This is true because the current is not amplified at all, before being impressed on the armature of the relay (65).

With the key (48) in the N A position, stations will continue to be tuned in as they sign off until the relay (67) is finally operated to disconnect the energy from the set.

If it is desired to operate the radio alone, the key (48) is thrown into the N A position. The push button (28) is then operated to connect electrical energy to the set. The 100 relay (68) is energized to connect the energy to the radio receiving set. Inasmuch as the relay (22) is energized immediately upon the operation of the rectifiers (13 and 14), the circuit is complete for the slow to operate relay (69), and this relay is energized to 105 initiate the automatic tuning. Subsequent operations occur substantially as before described.

It may be that the operator desires to tune 110 in a predetermined station. In order that he may do this a calling device (73) is provided, together with a key (93'). This calling device may be of a type somewhat similar to that employed in the telephone art, 115 though preferably it is modified so that one revolution of the calling device will cause it to close its springs a large number of times. That is, it may be designed to send one hundred impulses. These impulses are adapted 120 to actuate a stepping magnet (62) that is arranged to advance the rotor of a condenser (61) through 180 degrees by means of the pawl and ratchet (60).

The call letters of the various broadcast- 125 ing stations may be noted on the dial so that the required number of impulses may be sent to cause the rotor of the condenser to be advanced to the desired point at which the input circuit of the detector (54) is res-

onant, or approximately so, to the broadcasting carrier frequency of the station. The calling device (73) and the key (93') may be located with the phonograph, or at any 5 desired point at a distance therefrom.

In order to properly operate the calling device (73) the operator throws the key (93'). As a result of the operation of this key, a circuit is completed after the stepping 10 magnet (62) through the off normal springs (91') and armature (90'). The stepping magnet was intermittently operated by a buzzer action until the rotor of the condenser is placed in its predetermined 15 normal position. At this point the circuit of the stepping magnet is opened at the off normal springs (91'). The calling device is then operated so that the desired number of 20 impulses are sent to advance the rotor of the condenser, to the predetermined position. The relay (69) is operated after an interval of time to complete a circuit for the motor (59) providing the voice current relay (20) has not been operated. The operation of the 25 motor (59) serves to tune in the desired station, inasmuch as the rotor of the condenser has been placed in approximately the desired position, and the subsequent motion of the rotor is merely to tune this station in 30 properly. This result will be brought about if the station is broadcasting, inasmuch as it is the closest station to the setting of the rotor of the condenser. If a station does not happen to be broadcasting at this time, 35 another station will automatically be tuned in, although the operator may press the release key (93') and select another desired station.

It is desirable in some communities where 40 both direct and alternating current is supplied to the various districts, that the machine be adapted to operate equally well with direct current, as well as alternating current. Means provided for accomplishing 45 this result will now be described.

It will be assumed that the source (74) is supplied with direct current. When the button (28) is pressed as before, the relay (66) is energized to connect energy through the 50 high impedance relay (71). This relay responds to direct current to attract its armature (85), thereby completing a circuit for the harmonic relay (72) by way of armature (86), and its back contact. The armature (86) of this relay is tuned as mentioned before to respond to 60 cycles. This armature is also polarized. The armature (86) is now operated so as to break the contact which includes its own circuit. The armature then 55 swings back to again close the circuit. This operation continues at the rate of 60 times a second. The current through the primary of the transformer (12) is thus interrupted 60 times a second. By the action of the 65 transformer, 60 cycle alternating current is

induced in the secondary windings; the voltage of this current being proportionately of the proportion of the turns in the secondary windings, to the turns in the primary winding.

The relay (72) thus operates essentially in the same manner as the relays employed in the harmonic converters used in the telephone art to create alternating currents. The contacts may be somewhat larger, so that the required amount of current will be supplied to the device. The current impressed upon the rectifiers and the other portions of the circuit is thus substantially the 60 cycle alternating current of the same character as is obtained from the usual commercial sources, so that the apparatus will function in the same manner as before. Thus, by the provision of the relay (71) and the harmonic converter (72) whenever the device is connected to a direct current source, the relay (71) is automatically operated to initiate the operation of the harmonic converter (72), to supply alternating current to the device.

It will be seen that I have provided simple and efficient means for automatically pre-selecting any one of a plurality of broadcasting stations, one after the other, for automatically selecting a predetermined broadcasting station, for automatic stopping of the playing of the record, and the switching in of the radio receiving set at desired times, as well as a number of other desirable features that have been described in the foregoing specification.

It is to be understood that while I have shown one particular embodiment of my invention, together with the means for carrying it out, that I do not wish to be limited to the specific means employed but desire to protect by Letters Patent, such changes, modifications and deviations as come within the scope of the appended claims.

I claim:

1. In a radio receiving system, a radio apparatus, means for supplying operating current to said apparatus, a tuning element for rendering said apparatus responsive to different frequencies, means for automatically actuating said element until a station is tuned in, means for automatically tuning in another station when reception from said first station is interrupted, and voice current responsive means for automatically disconnecting said operating current when no waves are received for a predetermined period.

2. In a radio receiving system, a radio apparatus, a tuning element for rendering said apparatus responsive to waves of different frequencies, means for supplying operating current to said apparatus, and voice current responsive means for automatically disconnecting said operating current when reception is interrupted for a predetermined period.

3. In a radio system, a receiving apparatus, a source of operating current for said apparatus, a switch for connecting said source to said apparatus, a magnet for operating said switch, and means responsive to the cessation of broadcast signals for energizing said magnet to operate the switch.

JOHN E. GARDNER.
